COMBINED CLOSET AND TABLE

Application filed May 29, 1931. Serial No. 541,068.

This invention relates to cabinets for the dining room or kitchen, of that general type in which the front of the cabinet may be lowered to provide a table.

5 An object of the invention is to provide a cabinet in which the legs for the table are hinged at the top to the top of the door frame in such manner as to gravitate to operative position while the door frame with the doors 10 is being lowered to the horizontal and will be locked against collapse when in use to provide a table.

A further object is to provide a cabinet of the type described in which the transverse 15 top member of the legs is pivoted to the door frame by means of a pin carried within an inclined slot in opposite angle irons carried by the door frame near the top, the legs being caused to move longitudinally of the slotted 20 angle irons by means of a novel hinged prop of substantially U-shape, which draws the legs from underneath the molding of the cabinet to permit the door frame, with the doors attached thereto, being lowered to the 25 horizontal to form the table.

A still further object of the invention is to provide the door frame with legs which close flat against the front face of the door frame when the door frame is raised to form a 30 closure for the front of the cabinet and underlie the molding or ledge at the top of the cabinet so that the table may serve as an attractive and artistic door for the cabinet without disclosing its character of a table.

35 With the above and other objects in view the invention consists in certain novel details of construction and combinations of parts hereinafter fully described and claimed, it being understood that various modifications 40 may be resorted to within the scope of the appended claims without departing from the spirit or sacrificing any of the advantages of the invention.

45 In the accompanying drawings forming part of this specification,

Figure 1 is a perspective view showing the cabinet with the doors dropped to the horizontal to provide a table,

50 Fig. 2 is a front elevation of the cabinet

with the doors in vertical position to conceal the shelves,

Fig. 3 is an end elevation of the cabinet, with the parts in the position shown in Fig. 2,

Fig. 4 is an enlarged detail sectional view 55 showing the doors and legs positioned against the front of the cabinet and underlying the top molding of the cabinet,

Fig. 5 is a vertical sectional view taken on the line 5-5 of Fig. 4, showing the rear faces 60 of the legs together with their connecting transverse top member, and showing the U-shaped prop carried by the legs and cross member,

Fig. 6 is a fragmentary detail sectional 65 view showing a device for locking the legs to the door frame in released position,

Fig. 7 is a fragmentary sectional view, with parts in elevation, showing the legs and transverse cross member thereof underlying 70 the door frame and the ends of the doors to positively prevent opening of the doors when the device is in use as a table, and

Fig. 8 is a fragmentary side elevation of the parts of the table shown in Fig. 4 but in 75 position to form the table.

Referring now to the drawings in which like characters of reference designate similar parts in the various views, a cabinet 10 is shown having shelves 11 in the upper portion 80 thereof and drawers 12 in the lower portion thereof. The cabinet is closed at the top by the usual head 13 which projects at the front outwardly beyond the front of the cabinet and is equipped with the usual molding 14. 85 The cabinet is provided with a ledge 15 above the drawers, which is disposed at such a height as to occupy a position corresponding with the table.

In further carrying out the invention, a 90 door frame is fitted to the front of the closet and comprises side members 16 and a cross member 17 at the top. As best shown in Fig. 2, the door frame is hinged at the bottom to swing outwardly and downwardly by means 95 of hinges 18 secured to the ledge 15 and to the front faces of the side members 16.

Doors 19 are hinged to the side members 16 of the door frame and when closed lie within the plane of the frame with their inner faces 100

flush with the inner side of the door frame to form a table with a level surface, as will hereinafter appear. Suitable handle knobs 20 provide means for opening and closing the doors.

Legs 23 connected at the top by a cross member 24 are provided to support the outer end of the table formed by rocking the door frame with the attached doors downwardly to the horizontal. A substantially U-shaped prop 25 is confined by metal straps 26 within a U-shaped groove 27 formed in the cross member 24 and legs 23. The prop is thus hinged to the legs at the bight or cross member of the prop. The terminals of the prop are pivotally connected to hinge ears 28 carried by the side members 16 of the door frame, pivot pins 29 being passed through the ends of the prop and through the hinge ears 28 to effect this pivotal connection of the prop with the door frame.

To slidably and pivotally mount the legs on the door frame, a pair of angle irons 30 are secured to the side members 16 of the door frame, as best shown in Fig. 1, by means of screws or other connectors, and the flanges of the angle irons are provided with longitudinal slots 31 which extend obliquely with respect to the major axes of the flanges, as best shown in Fig. 8. Pins 32, as best shown in Figs. 2, 4, 5 and 8, are mounted in the outer edges of the legs 23 and are slidably engaged in the slots 31 in the flanges of the angle irons. It will be observed that the ends of the slots 31 are offset inwardly from the slots toward the door frame, as shown at 33 in Figs. 4 and 8.

By now referring to Figs. 4 and 8, it will be seen that when the legs are rocked to upright position against the front of the door frame, the pins 32 are disposed at the upper ends of the slots 31. When the door frame with the attached doors is being rocked downward to the horizontal to the position shown in Fig. 8, the pins 32 ride longitudinally of the slots 31, and, as the legs arrive in vertical position, the prop 25 forces the pins 32 into the offset ends of the slots 31 so that the legs are locked against collapse.

As best shown in Fig. 7, when the legs are positioned to support the door frame and doors to form a table, the transverse member 24 which connects the legs extends transversely across both the doors 19 so that the doors are positively held against opening downwardly. It will be further observed, by referring to Fig. 7, that the doors and door frame are so supported in horizontal position when forming a table by the ledge 15 of the cabinet that a strong, rigid table is produced to withstand severe conditions of service.

The slots 31 in the angle irons permit the legs and cross member 24 thereof sliding upwardly underneath the molding 14, about one-half inch, as best shown in Fig. 4, when

the table is moved to the vertical so that the doors and frame are held by the molding to form a closure for the front of the cabinet without the use of other securing devices.

To convert the cabinet to provide a table, the legs 23 are grasped and pulled outwardly. When the legs 23 are drawn outwardly, the cross member and legs move downwardly in the slots of the angle irons and disengage from in rear of the molding 14 to release the door frame from the front of the cabinet. The door frame 16 may then be rocked downwardly on the hinges 18 to the horizontal, the legs meanwhile sliding longitudinally of the angle irons 30 until, at their limit of movement, the pins 32 lodge in the offset ends 33 of the slots, in which position of the parts the prop 25 operates to hold the legs upright. During such movement of the parts, the angular inclination of the slots facilitates the pins 32 riding freely along the slots while being moved by the hinged prop 25 so that it will require but slight muscular effort to convert the cabinet into a table. A reverse movement of the parts will restore the table to provide a closure for the shelves, as will be understood.

Having thus described the invention, I claim:

1. A cabinet having a front hinged at the bottom to open to a horizontal position for use as a table, a stop on the top of the cabinet legs for supporting the front in horizontal position, means pivotally and slidably attaching said legs to the upper end of the front and adapted to dispose said legs in rear of said stop to hold the front upright to form a closure for the cabinet, and props hinged to the front and to the legs for preventing collapse of the legs.

2. A cabinet provided with a front hinged at the bottom to open to horizontal position for use as a table, laterally opening doors hinged to the front, legs connected by a cross piece at the top, connections between the front and the cross piece permitting of combined sliding and pivotal movement of the legs to position the cross piece underneath the doors to hold the doors closed when lowered to the horizontal, and props hinged to the front and to one of the legs for preventing collapse of the legs.

3. A cabinet having a front hinged to open to a horizontal position for use as a table, a molding on the top of the cabinet, legs connected by a cross piece at the top, a U-shaped prop having the bight hinged to said cross piece and extending therealong and having the terminals hinged to said front, said prop being adapted to be confined between the legs and the front when the front is rocked upwardly to close the cabinet, and combined pivotal and sliding connections between said legs and said front permitting of the legs being moved by the prop to upright position under-

neath the molding to hold the front in upright position.

4. A cabinet having a door frame hinged at the bottom to open to a horizontal position, a molding carried by the cabinet, laterally opening doors carried by the frame, angle irons carried by the frame and having slotted flanges, legs having pins engaging in said slotted flanges and slidably and pivotally mounting the legs upon the door frame, and a prop hinged to the door frame and to the legs to slide the legs up in back of the molding to hold the door frame upright.

5. A cabinet having shelves in the upper portion thereof and drawers in the lower portion thereof, there being a ledge projecting forwardly from the cabinet between the shelves and drawers, there being a molding projecting forwardly from the top of the cabinet, a door frame hinged at the bottom to said ledge to open to a horizontal position, laterally opening doors carried by the frame, legs hingedly and slidably connected to the door frame and adapted to fold against the front of the frame underneath said molding, and props for supporting the legs upright when the door frame is lowered to the horizontal, said props sliding the upper ends of the legs upwardly underneath the molding strip to hold the doors locked against the front of the cabinet in vertical position.

6. A cabinet having a front hinged to open to a horizontal position for use as a table, a molding strip carried by the cabinet, angle irons carried by the front having flanges provided with slots disposed at an angle to the longitudinal axes of the flanges, legs having pivot pins pivotally and slidably engaging in said slots, the slots being offset at the ends to receive said pivot pins, and props hinged to the front and to the legs for pivotally and slidably moving said pins in said slots to dispose the legs in rear of the molding to hold the front closed against the cabinet and locking the pins in said offset portions of the slots to lock the legs to support the table horizontally.

In testimony whereof I affix my signature.
EDGAR S. BOLLES. [L. s.]
